UNITED STATES PATENT OFFICE.

GEORGE WHEALE, OF MEADOWBROOK, PENNSYLVANIA.

FUSED TEST CLAMP-INSULATOR.

1,144,672.

Specification of Letters Patent. Patented June 29, 1915.

Application filed January 27, 1914. Serial No. 814,713.

To all whom it may concern:

Be it known that I, GEORGE WHEALE, a citizen of the United States, residing at Childrens Village, Meadowbrook, in the county of Montgomery and State of Pennsylvania, have invented certain new and useful Improvements in Fused Test Clamp-Insulators, of which the following is a specification.

10 This invention relates to an improved means for connecting sections to a line wire with an insulator so that if excessive current passes through the wire the connection between the two sections of the line 15 wire may be broken and thus the flow of current interrupted.

Another object of the invention is to so 20 construct the insulator block and wire engaging collars that the collars may be securely connected with the insulator block and prevented from moving longitudinally thereon.

Another object of the invention is to so 25 construct the fuse strip that it may be easily renewed when burnt out.

Another object of the device is to allow 30 the opening of sections of wire without cutting the wire.

Another object of the device is to allow 35 the opening of sections of wire for testing purposes between one station or exchange and another station or exchange.

Another object of the device is to provide 40 a terminal for a wire entering a cable box and coming out again.

This invention is illustrated in the accompanying drawings wherein:

Figure 1 is a side elevation showing the 45 device in use; Fig. 2 is a transverse sectional view through the device to show the manner of mounting the collars; Fig. 3 is a sectional view taken on the line 3—3 of Fig. 1; and Fig. 4 is a view of the blank from which one of the collars is formed.

50 The insulator block 10 may be formed of any suitable material but is preferably formed of glass or china. Annular ribs 11 and 12 are formed upon this block to provide seats 13 which are curved in cross section as shown in Fig. 1. Collars 14 and 15 are mounted in the seats 13 formed by the ribs 11 and 12, each collar being formed from a blank shown in Fig. 4. This blank 55 is formed of copper or some other suitable metal which will conduct electricity

and is crescent shaped in cross section as shown in Fig. 3 so that when the strip is bent around the insulator the collar will conform to the contour of the seat in which it is placed and thus be held tightly in 60 place. Sectional bolt members 17 extend from the end portions of the strip 16, the bolt members being formed in two sections so that the wires may pass through the bolt members and be clamped by these bolt members when the winged nuts 18 are in place.

When this device is in use the collars are first placed about the insulator with the bolt at one end of each of the collars passing through one of the openings 19. The wires 70 20 and 21 are then placed about the collars as shown in Fig. 2 and passed through the slots of the bolts. The winged nuts 18 can now be placed upon the outer bolts and tightened so that the wires will be tightly 75 gripped and held in place. The fuse strip 22 is now placed upon the lower one of the inner bolts and is then swung upwardly so that its hooked end 23 will engage the upper inner bolt. The winged nuts are now placed 80 upon the inner bolts and are tightened so that the fuse strip will be held in tight engagement with the wires and collars.

When the current flowing through the wires 20 and 21 is not above the desired 85 amount it will pass through the fuse strip 22 without injuring the strip. If, however, the current is excessive the fuse strip 22 will be burnt through, thus breaking the circuit and prevent the current from passing from the wire 20 to the wire 21. This will prevent any danger of the machine which is being operated from being injured by the 90 excessive current. When the fuse 22 is burnt through the operator can regulate the generator so that the current passing from the generator will be reduced to the desired amount and a new fuse strip can be easily 95 put in place by removing the winged nuts which hold the strip in place and mounting 100 a new strip.

I have thus provided a device by means of which two sections of an electric line wire may be connected to permit current to pass from one section to the other which is so constructed that if the current increases beyond the predetermined amount the connection will be broken. It is of course obvious that the fuse strip 22 is formed of some material which will melt a great deal more 110

readily than the collars 14 and 15 and therefore the collars will not be melted at the same time the strip is.

What is claimed is:

- 5 1. A device of the character described comprising an insulator block, collars carried by said block in spaced relation, each of said collars being formed from a strip of electricity conducting material, the strip 10 being bent around said block, means for securing the inner end portion of said strip to the intermediate portion thereof whereby the free end portion of said strip will extend from said block, means carried by the 15 free end portion of each of said strips for engaging an electric conductor, and a fuse element removably connected with said collars.
2. A device of the character described 20 comprising an insulator block, collars carried by said block in spaced relation, each of said collars being formed from a strip of material bent about the block, a stem extending from the inner end portion of said strip and passed through an opening formed in said strip intermediate its length, said stem being slotted longitudinally, a stem extending from the outer end portion of said 25

strip and provided with a longitudinally-extending slot whereby a conducting wire 30 may be passed around each of said collars through the slots of said stems, a fuse element removably mounted upon the inner stems of said collars, clamping means mounted upon said stems for clamping said conducting wires to said collars and releasably holding said fuse element upon said inner stems.

3. A strip for releasably connecting a wire with a support provided with openings positioned at points intermediate the center and the ends of the strip, securing means carried by the end portions of said strip for permitting the strip to be secured about a support with the free end portion of the 45 strip extending in a selected direction from the support, and means for releasably holding a wire about the strip and in engagement with said securing means.

In testimony whereof I affix my signature 50 in presence of two witnesses.

GEORGE WHEALE.
